UNITED STATES PATENT OFFICE

JOSEPH O. TURNER, OF WINSTON-SALEM, NORTH CAROLINA, ASSIGNOR TO THE MENGEL COMPANY, OF LOUISVILLE, KENTUCKY, A CORPORATION OF NEW JERSEY

FASTENER-SETTING MACHINE

Application filed November 30, 1928. Serial No. 322,790.

The present invention pertains to a machine for setting stays or fasteners in containers, such as boxes, crates or the like.

The machine is especially designed for applying or setting the type of fastener covered by my Patent No. 1,692,596, dated November 20, 1928, this type of fastener being constructed so that it will connect a rack strip and a side of a crate and, when set, serves to grip both of these members and thus prevents bulging of the side of the container. As the rack strips or partitions of these crates form its principal strengthening or reinforcing means, it is important that they be securely fastened to the sides of the crate. It is therefore the primary purpose of the present machine to rigidly and firmly secure the fastener in place.

A further important object is the designing of a machine which not only serves to efficiently set the fastener in the parts of the crates which it connects together, but performs this function quickly and neatly. It is also intended to provide a machine of simple, durable construction in the operation of which highly skilled employees are not necessary.

Other objects will appear hereinafter.

A practical embodiment of the invention is disclosed in the accompanying drawings, wherein,

Fig. 1 is a side elevation of the machine partly in section, the parts being shown in their normal or rest positions preparatory to operating on a fastener which has been positioned on a crate located in the machine;

Fig. 2, a fragmentary perspective of the fastener setting mechanism;

Fig. 3, a similar view showing the fastener setting jaws and the plunger head for actuating the jaws, these parts being shown separated from the complete fastener setting mechanism of Fig. 2 for sake of clearness.

Fig. 4, a vertical section taken on line 4-4 of Fig. 1;

Fig. 5, a horizontal section taken on line 5-5 of Fig. 1, the crate supporting table being partially broken away to show clearly the details of the operating mechanism for the machine;

Fig. 6, an enlarged perspective view showing the positions of the fastener setting jaws with reference to one of the fasteners and the crate to which it is applied.

Fig. 7, a vertical section on line 7-7 of Fig. 1 disclosing the automatic clutch disengaging means and brake;

Fig. 8, a fragmentary view similar to Fig. 1 with the fastener setting mechanism in its lowered position or operative position at the completion of a setting operation;

Fig. 9, a fragmentary view similar to Fig. 4 with the fastener setting means again shown in its lowered or operative position at the completion of the setting operation;

Fig. 10, a side elevational view, partly in section, of a modified form of fastener engaging jaw provided with anti-friction means;

Fig. 11, a horizontal section taken on line 11-11 of Fig. 8; and

Fig. 12, a horizontal section taken on line 12-12 of Fig. 8.

The machine comprises a base 1 on which is rigidly mounted an upright framework made up of vertical posts 2, 3 and transverse connecting members 4, 5 and 6. Mounted for limited vertical reciprocatory movement on the upper portions of members 2, 3 is a horizontal cross member 7 having an integral, forwardly extending arm 8 projecting centrally from the front face thereof. Cross member 7 is provided at each end with a removable bearing plate 7', whereby it may be secured in place for sliding movement up and down on the upright member 2, 3 of the frame of the machine. As shown clearly in Figs. 1 and 4, upper arm 8 is provided on one of its faces with a horizontal rib 9, the upper face of which has formed therein a longitudinally extending tapered groove 10 which is open at the outer end of the arm for a purpose which will appear hereinafter.

Connected centrally to the rear face of the cross member 7 by means of a suitable pin 11 is a connecting rod 12, which is disposed in an upright position between the side posts 2, 3 of the frame of the machine. At its lower end connecting rod 12 is connected by a suitable pin 13 to one face of a gear wheel 14, pin 13 being disposed eccentrically on the gear wheel

80

75

85

90

95

70

so as to form a common crank and connecting rod connection between gear 14 and upper cross member 7.

Gear wheel 14 is keyed to the forward end of a horizontal shaft 15 mounted in suitable bearings 16, 17 fastened to the top of base 1. Also mounted on suitable bearings 18, 19 on the top of base 1 and parallel to shaft 15 is a second horizontal shaft 20 on the forward end of which is keyed a spur gear 21 with which gear 14 on shaft 15 meshes. Mounted for free rotation on shaft 20 is a gear wheel 22 which is driven in a counter-clockwise direction, as indicated in Fig. 4, by an electric motor 23 through a spur gear 24. Referring to Fig. 4 again, it will be seen that this results in clockwise rotation of gear wheel 14 looking from the front of the machine.

There is also mounted on shaft 20 a collar 25 which is keyed to the shaft for rotation therewith, but is free to slide longitudinally on the shaft. Secured to the adjoining face of gear wheel 22 is an expanding shoe clutch 26, the operative parts of which are connected by toggles 27 with collar 25 so that the clutch is engaged when the collar is moved towards gear wheel 22. Cooperating with collar 25 is the usual shipper lever 28, whereby collar 25 may be moved to engage clutch 26. At its lower end shipper lever 28 is pivotally connected to base 1. Intermediate its ends there is pivotally connected to shipper lever 28 a rod 29, the latter being pivotally connected at its forward end to the outer end of one arm of a bell crank pedal lever 30. Lever 30 is pivoted on base 1 at 31 and the outer end of its longitudinal arm has the usual foot pedal 32.

With the arrangement described, it thus will be seen that depression by the operator of foot pedal 32 will result in engagement of clutch 26 through the interconnected parts described. With electric motor 23 running and thus driving gear wheel 22, engagement of the clutch will result in motion being transmitted to gear wheel 14, which, as heretofore stated, rotates in a clockwise direction as indicated by the arrow in Fig. 4. The parts as they appear in this figure are in their normal inoperative positions, namely, the positions which they automatically assume when the parts come to rest after a fastener setting operation. At this time pin 13, whereby rod 12 is connected to gear wheel 14, is at the highest point that it reaches during the operation of the machine, and consequently upper cross member 7 and its arm 8 are in their extreme upper position.

As shown in Figures 1, 4 and 5 there is mounted on horizontal shaft 15 a collar 33 provided with a transversely projecting arm 34. Arm 34 is adapted to be secured in any desired angular position on shaft 15 by means of a set screw 35 mounted in collar 33. The

purpose of arm 34 is to provide automatic means adapted to act on a cooperating portion 36 formed on the adjacent arm of shipper lever 28 to disengage the clutch 26 and stop the machine upon the completion of each fastener setting operation. In the normal or inoperative position of the parts shown in Figs. 1, 4 and 5, lever 34 has just passed out of engagement with the cooperating portion 36 of shipper lever 28 after operating upon the same to cause disengagement of clutch 26. The cooperating surfaces of arm 34 and portion 36 are shaped suitably, of course, to bring about the desired action.

In order to aid in automatically bringing the machine to a complete stop immediately upon disengagement of the clutch through the operation of arm 34 on shipper lever 28 there is provided on shaft 15 a brake drum 37 with which cooperates a brake band 38, one end of which is secured directly to base 1 and the other end of which is secured to the base through an interposed coil spring 39.

A lower cross member 40 having a forwardly projecting arm 41 is located in the machine below upper cross member 7 and its forwardly projecting arm 8, and is adapted also to be reciprocated upwardly and downwardly intermittently during the operation of the machine. During this movement, cross member 40 and its arm are guided in part by uprights 2, 3 of the machine frame for which purpose each extremity of cross member 40 is provided with a rearwardly projecting extension 42, see Fig. 12, to the rear faces of which is removably secured a plate 43. Lower cross member 40 and its arm 41 receive their movement through upper cross member 7 and its corresponding arm 8 when the latter are operated by connecting rod 12. For this purpose, upper and lower cross members 7, 40 are connected together at each side of the machine by a rod 44, the lower end of which is fixed by means of a set screw or the like in a perforated lug 45 provided on lower cross member 40. At its upper end, rod 44 extends through a perforated lug 46 on upper cross member 7 and has a spacer tube 47 loosely mounted thereon above lug 46. A stop collar 48 is secured on the upper end of rod 44 by a set screw or other suitable means and is adapted to be engaged by tube 47 as upper cross member 7 ascends to raise lower cross member 40 to its uppermost position. Mounted on rod 44 and interposed between lugs 45 and 46 is a coil spring 49 which, as will appear hereinafter, permits continued downward movement of upper cross member 7 and its arm 8, after lower cross member 40 and its arm 41 have reached their lowermost position.

Mounted in the machine below lower cross member 40 and its arm 41 is an adjustable table 50 having a pair of brackets 51, 52 formed on its under side and provided at

their rear edges with bearing portions 53, 54 adapted for sliding engagement with posts 2, 3 of the framework. To the rear edges of bearings portions 53, 54 there is removably secured a transverse plate 55 which serves in part to guide the table in its up and down movement during any adjustments thereof. A cross member 56 connects the bearing portions 53, 54 of the table and is provided centrally with a bracket 57 having a threaded opening therethrough. The upper threaded portion of shaft 58 extends through the threaded opening of bracket 57, while the lower end of shaft 58 projects through openings provided in the arms of a bifurcated bracket 59 secured to cross member 4 of the framework. Disposed between the arms of bracket 59 is a hand wheel 60 which is keyed to shaft 58 so that manipulation of hand wheel 60, according to the direction of rotation of the hand wheel, will result in a raising or lowering of table 50.

Cross member 5 of the framework of the machine not only serves as a stop for limiting the downward movement of lower cross member 40 and its arm 41, but also acts as a transverse stop or abutment for the container being operated upon. A longitudinal guide or abutment 61 for the container is shown mounted on table 50 in Fig. 4. Guide 61 is removably and adjustably held in place by bolt and nut 62 extending through a perforation in table 50 and an open ended slot in the base of the guide.

Mounted on upper arm 8 and lower arm 41 are the cooperating means which serve to set the fastener in place in the container being operated on. This mechanism comprises a pair of fastener setting jaw carrying members 63, 64, these members being secured rigidly together as shown most clearly in Fig. 2. Jaw carrying member 63 is provided with an extension 65 adapted to engage with the upper face of reciprocating arm 41. This face of arm 41, as appears from Figs. 2 and 4, is formed with a slot 66 which is of inverted T form in cross section. Jaw carrying member 63 is secured to arm 41 by means of a pair of T bolts and wing nuts 67, the heads of the bolts being slipped into the outer open end of slot 66 and the wing nuts tightened up after jaw carrying member 63 is in the desired position on arm 41. Extension 65 has a rib 68, see Fig. 4, which also engages with slot 66 to firmly hold member 63 in place on the arm.

On their under faces, jaw carrying members 63, 64 are formed so as to provide a pair of depending spaced extensions 69, 70, thereby providing a longitudinal slot 71. The under face of member 64 is also provided with an extension 72 which is spaced from extensions 69, 70 so as to provide a transverse slot 73 into which slot 71 opens at one end. Both slot 71 and slot 73 are open at their under sides so as to receive the side and partition

walls of the container being operated on, as will appear shortly.

Extensions 69, 70 are each formed with a transverse passageway which is open at both ends. Mounted in these passageways for free reciprocating movement are fastener setting plungers or presser members 74, 75. The inner ends of these plungers are provided with a series of vertically disposed ribs 76 in order to facilitate setting of the fastener in the container.

Extension 72 is also provided with a horizontal passageway therethrough in which is mounted for reciprocatory movement a third fastener setting jaw or presser member 77. The inner end of jaw 77 is provided with an overhanging lip 78 which is curved on its under surface to cooperate in the proper setting of the fastener, as will appear hereinafter.

Each of the two side jaws 74, 75 and end jaw 77 is provided on one face with an inclined groove 79. Jaw carrying members 63 and 64, in addition to the transverse passageways in which jaws 74, 75 and 77 are located, is provided with vertically disposed passageways 80, 81, 82, which intersect the transverse passageways and are open at their upper and lower ends. In each of these three vertical passageways, there is mounted for free reciprocal movement, a jaw actuating plunger 83. The lower portion 84 of each plunger 83 is of reduced thickness and has formed thereon an inclined rib 85. Each of these ribs 85 is disposed in the corresponding inclined groove 79 in the three jaws 74, 75 and 77. At their upper ends, the three plungers 83 are rigidly connected to a plunger head 86, the latter being provided with a horizontal open ended slot 87 on one side thereof. Plunger head 86 is mounted removably in place on upper arm 8 by slipping the plunger head on to the outer end of rib 9 provided on one side of arm 8 for this purpose. A tapered rib 89 on plunger head 86 and a corresponding groove 10 on rib 9 serve to securely interconnect the parts, while an additional bearing surface for the plunger head is provided by vertical surface 91 on the arm 8. It will thus be evident that any relative movement between plunger head 86 and the jaw carrying members 63, 64 will result in inward or outward movement of jaws 74, 75 and 77 by reason of the coaction of inclined ribs 84 and inclined slots 79. The arrangement is such that the jaws will be moved inwardly in synchronism as upper arm 8 and lower arm 41 are brought closer together, and, as these arms move apart the three jaws will move outwardly in their respective passageways.

In use, a crate or other similar container 92 is positioned on the table 50 with one side 93 thereof against guide 61 and adjoining side 94 against cross member 5. Guide 61 is ad-

justed then on table 50 and plunger head 86 and jaw carrying member 63 adjusted on arms 8 and 41, so that, when arms 8 and 41 move downwardly to perform a fastener setting operation, side wall 93 of the crate will project freely into slot 73 and partition 92 of the crate into slot 71 in the under face of the jaw carrying mechanism, as shown in Fig. 5.

Before operating the machine to set a fastener in place in the crate, it must be adjusted for the height of the particular size of crate being used. This is accomplished by vertical adjustment of table 50 through hand wheel 60. First, it is necessary to set the machine in motion by depressing pedal 32. This throws in clutch 26 and through the interconnected mechanism causes downward movement of arms 8 and 41, the movement of the arms being in synchronism for the first portion of their downward travel. As shown in Fig. 4, when the arms are in their uppermost position, they are separated by gravity and by coil springs 49, 49, so that spacing collars 47, 47 abut stop collars 48, 48 at their upper ends. The arrangement and proportioning of the parts is such that, in this position, fastener setting plungers 74, 75 and 77 are in their outermost and fully retracted positions in order to freely receive the upper edges of the crate 92 when the fastener setting mechanism is lowered.

As stated, arms 8 and 41 at first move downwardly together, but as soon as lower cross member 40 comes in contact with the upper edge of the stationary cross member 5, member 40 becomes stationary. As long as arms 8 and 41 move together, the fastener setting jaws 74, 75 and 77 remain in their fully retracted position as shown in Fig. 4. However, with the arrangement described, when cross member 40 and its arm 41 come to a stop, upper cross member 7 and its arm 8, by reason of coil springs 49, 49 are permitted to continue their downward movement. This results immediately in simultaneous inward movement of fastener setting jaws 74, 75 and 77 through the inclined ribs and grooves before described.

With the machine thus operating, hand wheel 60 is manipulated so as to raise or lower table 50 and the crate thereon until the upper edges of the crate are but a slight distance below the under face of jaw carrying members 63, 64, when the latter are in their lowermost position as shown in Figs. 8 and 9, or just enough to accommodate the fastener element.

The fastener 95 referred to is shown most clearly in Fig. 6 in which it appears in its completely set condition on the crate, while in Figs. 1 and 4 the fastener is shown as it appears before the setting jaws have acted on it.

As appears from Fig. 6, fastener 95, which

is made of sheet metal, comprises a body portion 96 having an extension 97. On the sides of body portion 96 there are formed integral depending tongues 98, 99 and end extension 97 has a similar tongue 100 arranged at right angles to the first mentioned tongues. Each of the three tongues, 98, 99 and 100, is provided at its lower end with inturned spurs 101 adapted to engage firmly the material of the crate when the tongues of the fastener are bent inwardly to secure the fastener thereon. It will be clear that the body portion 96 and tongues 98, 99 of the fastener engage the partition 94 of the crate, while extension 97 and tongue 100 are adapted to engage the side 93 thereof so as to bind these two parts of the container firmly and rigidly together. The form of the fastener 95 before it is set by the machine is shown clearly in Figs. 1 and 4. In this condition, it will be noted that the tongues 98, 99 and 100 are flared outwardly somewhat so as to permit the fastener to be slipped readily over the upper edges of the crate.

With the fastener 95 so positioned on the crate, the operator depresses pedal 32, as a result of which the fastener setting mechanism carried by arms 8 and 41 descends until partition 94 and side 93 of the crate are disposed within intersecting slots 71, 73 of the fastener setting mechanism. At this time it is impossible for the fastener to slip out of place due to the presence of jaw carrying members 63, 64. As soon as cross member 40 strikes transverse member 5, arm 41 stops and the continuing movement of upper arm 8 results in fastener setting jaws 74, 75 and 77 moving inwardly until their inner ends are brought into engagement with the depending tongues 98, 99 and 100 of the fastener. Side jaws 74 and 75, which are disposed in alignment with each other, are brought thus simultaneously into engagement with the corresponding side tongues 98, 99, causing the tongues to be bent inwardly until their spurs 101 are embedded firmly in partition 94 of the crate, see Fig. 8. Simultaneously, end jaw 77 at its inner end engages with the end tongue 100 of the fastener and bends it inwardly until the spurs 101 thereon are embedded firmly in the outer face of side wall 93 of the crate. The overhanging curved lip 78 on jaw 77 acts on the fastener at the juncture of its extension 97 and end tongue 100, so as to shape and bind this portion of the fastener tightly about the upper edge of side wall 93 of the crate, and thus draw the partition wall 94 into close engagement therewith, see Figs. 6 and 9.

Upper arm 8 then ascends, causing fastener setting jaws 74, 75 and 77 to be retracted simultaneously. As soon as spacer tubes 47, 47 engage stop collars 48, 48, arm 41 and the fastener setting mechanism carried thereby also ascend until all of the parts

again assume the normal or inoperative position of Figs. 1 and 4. The machine is stopped automatically at this time by reason of the disengagement of clutch 26 caused by the camming action of arm 34 on projection 36 provided on shipper lever 28. As appears from Figs. 1, 4 and 5, the momentum of the parts of the machine is sufficient to carry arm 34 beyond the lowermost portion of projection 36, after which brake band 38 serves immediately to stop the mechanism. In other words, the complete cycle of operations necessary to set a fastener in a container is performed automatically by the machine as soon as the operator depresses pedal 32. The machine then comes to rest automatically in readiness for a repetition of the cycle of operations.

Reference is now had to the modification shown in Figure 10. Considerable friction between the parts is caused by the operation of inclined ribs 85 on plungers 83 in the inclined slots 79 in the fastener setting jaws 74, 75 and 77. In order to reduce this friction and to permit more efficient operation of the parts, in some cases it may be desirable to mount an anti-friction roller 102 in each of the jaws 74, 75 and 77 so that the roller projects slightly into the inclined slot 79 and into engagement with the under surface of the inclined rib 85. Slot 79 should be somewhat wider than rib 85 in order to permit proper coaction between the parts. Preferably, anti-friction roller 102 is mounted for free rotation on a small shaft 103, journaled at its ends in the sides of a slot 104, which opens on one side into inclined slot 79.

It will thus be seen that the machine described is designed for efficient and quick application and setting of fasteners in boxes, crates, or the like.

What is claimed is:

1. The combination in a machine of the character described of a reciprocable member; a second reciprocable member; fastener-setting means located on said first mentioned member; means on the second mentioned member for actuating said fastener-setting means upon relative movement of said members; means for effecting simultaneous movement of said members; and means displaced from the work operated upon for preventing continued simultaneous movement of said members and causing relative movement therebetween to actuate said fastener-setting means.

2. The combination in a fastener-setting machine of fastener-setting means mounted for movement as a unit; actuating means for said fastener-setting means also mounted for movement as a unit, said fastener-setting means being adapted to be operated by said actuating means upon relative movement of the fastener-setting means and the actuating means therefor; means for effecting simul-

taneous movement of said fastener-setting means and said actuating means; and means displaced from the work operated upon for preventing continued simultaneous movement of the fastener-setting means and its actuating means and causing relative movement therebetween to actuate the fastener-setting means.

3. In a fastener-setting machine, the combination of a frame; fastener-setting mechanism mounted for movement on the frame; actuating means for setting the mechanism also mounted for movement on the frame and adapted to operate said setting mechanism as a result of relative movement of the actuating means and the setting mechanism; a resilient connection between the setting mechanism and the actuating means; means for effecting simultaneous movement of the actuating means and the setting mechanism through said resilient connection; and means displaced from the work operated upon for stopping the movement of the setting mechanism before completion of the movement of the actuating means.

4. In a fastener-setting machine, the combination of a frame; fastener-setting mechanism mounted for bodily movement on the frame; operating means for the setting mechanism also mounted for movement on the frame and adapted to actuate the setting mechanism as a result of relative movement between the setting mechanism and the operating means; a slidable connection between the setting mechanism and the operating means; spring means tending to maintain said connection in extended condition; means for effecting simultaneous movement of the setting mechanism and its operating means through said slidable connection; and means displaced from the work operated upon for stopping the bodily movement of the setting mechanism before completion of the movement of the operating means.

5. The combination in a fastener-setting machine, of a head; a plurality of fastener-setting members mounted therein for reciprocatory movement and adapted for engagement with a single fastener; and a plurality of corresponding reciprocable actuating members for the fastener-setting members, one member of each pair of corresponding members being provided with an inclined slot and the other with a cooperating inclined rib for imparting movement to the setting member when the actuating member is moved.

6. In a fastener-setting machine, the combination of a head having a plurality of plungers mounted therein for reciprocatory movement and adapted for simultaneous engagement with a single fastener; a pair of said plungers being opposed to each other and another disposed substantially at right angles to said pair; and means for operating the plungers.

7. In a fastener-setting machine, the combination of a head; a series of plungers mounted for equal reciprocatory movement in said head towards and from a single point, one of said plungers being located normally further from said point than another; and operating means for the plungers.
8. In a fastener-setting machine, the combination of a head; three plungers mounted in said head for rectilinear movement towards and from a single point, two of said plungers being disposed in alignment with each other and the third located at right angles to said pair and further removed from said point than said pair; and operating means for the plungers.
9. In a fastener-setting mechanism, the combination of a head; a plurality of fastener-setting plungers mounted for reciprocatory movement in the head and adapted to engage a single fastener, the active end of one of said plungers being substantially flat except for a tapered lip formed thereon; and means for operating the plungers.
10. The combination in a fastener-setting machine, of a head, said head being provided with a plurality of horizontally disposed converging passages; fastener-setting plungers located for reciprocal movement in said passages and each provided on one side thereof with an inclined slot; and a plurality of actuating plungers mounted for reciprocatory movement in upright passages also provided in said head and intersecting said horizontal passages, the actuating plungers being provided with inclined ribs engaging the inclined slots in the fastener-setting plungers.
11. In combination in a fastener-setting machine, a frame; an upper arm mounted for reciprocation on the frame; a lower arm mounted for reciprocation on the frame; a head mounted on said lower arm; a plurality of fastener-setting plungers mounted for reciprocatory movement in said head, each of said plungers being provided with an inclined slot; a plurality of plunger actuating members mounted on said upper arm, said members being provided with inclined ribs engaging with the inclined slots on the fastener-setting plungers; and means for operating the upper arm to actuate the fastener-setting plungers.
12. An attachment for a fastener-setting machine having a pair of grooved and ribbed reciprocable arms and means for operating the arms comprising, in combination, fastener-setting mechanism provided with a tongue adapted to slidably engage the groove on one of said arms; operating mechanism for the fastener-setting mechanism provided with a slot adapted to be slidably engaged by the rib on the other arm; and means for securing the fastener-setting and operating mechanisms in adjusted position.
13. In combination, a jaw-carrying head

provided with permanent intersecting slots for the reception of a pair of walls of a receptacle being operated upon; a series of fastener-setting jaws mounted in said head; and means for operating said jaws.

14. The combination in a fastener-setting machine, of a frame; a member mounted for reciprocation on said frame; a second member also mounted for reciprocation on the frame; a fastener-setting mechanism having an adjustable tongue-and-groove connection with the first-mentioned reciprocable member; an operating mechanism for the fastener-setting mechanism having an adjustable tongue-and-groove connection with the second-mentioned reciprocable member; and means for securing the fastener-setting means in adjusted position.

15. The combination of a head; a series of fastener-setting plungers mounted for rectilinear movement in said head for setting a single fastener; operating means for the plungers; and anti-friction means interposed between said plungers and their operating means.

16. In a fastener-setting machine, the combination of a head; a series of plungers mounted in said head for rectilinear movement along and in close proximity to one of the faces of the head; and operating means for the plungers.

17. In a fastener-setting machine, the combination of a head having a plurality of spaced, depending portions on its under face, the space between a pair of said portions being adapted to receive one wall of a box being operated upon and the space between said pair of depending portions and another depending portion to receive an intersecting wall of said box; a series of plungers mounted for reciprocation in said depending portions toward and from a common point; and plunger operating means.

In testimony whereof I have signed my name to this specification.

JOSEPH O. TURNER.
